ATTORNEY

UNITED STATES PATENT OFFICE.

CHARLES L. TORREY, OF SAN JOSE, CALIFORNIA, ASSIGNOR OF SEVENTY PER CENT.
TO CHARLES A. SAWYER AND TWENTY-FIVE PER CENT. TO WILLIAM T. ALEXAN-
DER, BOTH OF SAN JOSE, CALIFORNIA.

BURNER-HEAD.

1,389,107.

Specification of Letters Patent. Patented Aug. 30, 1921.

Application filed November 10, 1920. Serial No. 423,087.

To all whom it may concern:

Be it known that I, CHARLES L. TORREY, a citizen of the United States, and resident of San Jose, in the county of Santa Clara and 5 State of California, have invented certain new and useful Improvements in Burner-Heads, of which the following is a specification.

My invention relates to a head for gas 10 burners of any suitable type.

It is the object of my invention to provide a burner head for any form of gas that will be simple in form, economical to manufacture and highly efficient in its practical application.

In burning any form of natural or artificial gas, and especially that form of gas generated in the various forms of hydro-carbon gas generators now in general use, it 20 is customary to provide a burner head in which the discharge openings for the gas are formed by sawing slots or drilling holes in a suitably formed cast-iron plate. This process is ordinarily a slow, laborious and expensive undertaking, frequently many saws being destroyed in the preparation of a single head. It is, therefore, a particular object of 25 my invention to provide a highly efficient and practical burner head that will obviate the necessity of sawing the slots or drilling 30 the holes above referred to.

In the drawing:

Figure 1 is a plan view of a burner head embodying my invention.

Fig. 2 is a sectional view on line 2—2 of Fig. 1.

Referring more particularly to the drawing, 1 indicates a gas chamber of any suitable form into which the gas to be burned is 35 charged through passage 2. At 3 is a plate of the same size as the top of chamber 1 and provided with a plurality of orifices as 4. A second plate is shown at 5 fitting in the upper portion of chamber 1 and provided with a 40 plurality of orifices 6, and spaced a distance, as 7, from plate 3 by suitable spacers as 8, and from the wall of chamber 1 by a space as indicated at 8^a. A bolt is shown at 9 threaded to engage nuts 10 and 11, the nut 45 11 securing plates 3 and 5 in the desired relation to each other and nut 10 securing the plates in position on the chamber 1.

If the space 8^a is provided the orifices 6 may be dispensed with, and if the orifices 6

are provided the space 8^a may be dispensed 55 with, or both space 8^a and orifices 6 may be provided. In fact, when the members 3 and 5 are in position on chamber 1 the space 8^a is the full equivalent of orifices 6.

In effecting my invention the orifices 4 in 60 plate 3 may be of any suitable size and arranged in any desired manner, and may be cast in the plate and used without any mechanical operations thereon. The orifices in 65 plate 5 may likewise be of any suitable size and arranged in any desired manner except that they must be so arranged that when the plates are assembled as described the orifices in plate 5 will be offset with relation to the orifices in plate 3. 70

In a head constructed in this manner the gas is discharged forcibly from chamber 1 through orifices 6 and against plate 3 where it is caused to spread out and flow with less velocity through orifices 4, since the orifices 4 are, in this case, larger than orifices 6. When a gas that is generated from fuel oil is 75 being used a practically perfect combustion thereof is secured since the plate 3 is heated by the burning gases thereover and the impinging of the gas against the under side of 80 this heated plate more perfectly vaporizes the same.

The space between plates 3 and 5 must, of course, be such that the gas cannot back-fire 85 even though the gas burns directly from the surface of plate 5 through orifices 4. In this construction the plate 5 also becomes somewhat heated and the gas must pass a distance between the two heated plates 3 and 5 before 90 reaching orifices 4 thereby.

A burner head constructed in this manner provides a clean hot flame and requires only the plain casting and assembling of the parts, thereby greatly simplifying and reducing the 95 cost of the head without in any manner reducing its efficiency but rather increasing the same.

It is to be understood of course, that I do not wish to limit the scope of my invention 100 to the specific form disclosed, as changes in form, size, proportions, and combination and relative arrangement and association of parts, members and features may be made within the scope of the appended claims. 105

I claim:

1. A burner head comprising a bowl shaped member, a gas inlet thereto, a perforated

plate arranged to cover the bowl shaped member, a second perforated plate spaced a distance from said first named plate and depending therefrom within said bowl shaped member, and means engaging both of said plates and said bowl shaped member for securing the same in fixed relation to each other.

2. A burner head comprising a bowl shaped

member, a gas inlet thereto, a perforated plate arranged to cover the bowl shaped member, a second perforated plate arranged within said bowl shaped member below said first mentioned plate, spacing elements between said plates, and a tie member axially arranged with relation to said plates and bowl shaped member.

CHARLES L. TORREY.
